UNITED STATES PATENT OFFICE.

RAYMOND HUFFORD, OF NEW YORK, N. Y., ASSIGNOR TO K. P. PRODUCTS COMPANY, INC., OF NEW YORK, N. Y., A CORPORATION OF NEW YORK.

GOVERNOR FOR INTERNAL-COMBUSTION MOTORS.

Application filed June 18, 1923. Serial No. 646,036.

To all whom it may concern:

Be it known that I, RAYMOND HUFFORD, a citizen of the United States, and a resident of New York city, in the county of New 5 York and State of New York, have invented certain new and useful Improvements in Governors for Internal-Combustion Motors, of which the following is a specification.

My invention relates to governors for internal combustion motors and has for its 10 object to provide a governor for this purpose which will be more efficient and accurate in its action, more easily and accurately regulated, and less expensive to construct than 15 those heretofore in use.

With these and other objects in view, which will be more particularly set forth in the specification, my invention consists of the novel details of construction and combination of parts hereinafter disclosed and 20 particularly pointed out in the claims.

Referring to the accompanying drawings:

Figure 1 is a sectional elevation. Figure 2 is a section on the line 2-2 of Figure 1. 25 Figure 3 is a section on the line 3-3 of Figure 1. And Figure 4 is an enlarged sectional view of the means for regulating the action of the piston which completes the closing movement of the valve which 30 restricts the flow of explosive mixture to the motor.

My governor is provided with a shell or body 1 having a cylindrical bore the upper or outlet end of which is reduced in diameter 35 to form a restricted throat 3. A spacing collar 4 is mounted in the upper portion of the bore. A spider 5 is mounted in the bore and held in spaced position therein by the spacing sleeve 4 and the sleeve 6 which is 40 formed with a contracted throat at 7. The spider is provided with a centrally-positioned cylinder 8. A guide 9 and cylindrical cup 10 are also formed in the spider. A passage 11 communicates between the cup 10 and cylinder 8. Into a threaded recess 12 in this spider 5 is screwed a bushing 13. The outer end of the bushing is threaded 45 to receive a threaded needle-valve 14, provided with a ribbed head 15 which extends 50 into a box-like chamber 16 formed on the body 1. A pointed pin 17, mounted in a guide chamber 18, is forced into contact with the head 15 by a spring 19 which serves to 55 maintain the needle-valve 14 in the position to which it has been adjusted. Mounted in

the cylinder 8 is a piston 20 having a guide stem 21, the upper end of which is reduced in diameter and threaded to receive the valve 22 which fits loosely in the cylindrical cup 10. Nut 23 serves to secure the valve 22 in position. Ports 24 are formed in the base of the valve 22. The lower end 25 of the piston 20 is reduced in diameter and threaded to receive a head 26. The outer wall of the cylinder 8 is threaded and a nut 27, having gear teeth 28, is mounted thereon. A spring 29, one end of which bears against the nut 27 and the other end against the head 26, tends to thrust the head and piston downward until the base of the valve 22 is 70 in contact with the bottom of the cup 10. The resistance of the spring against the upward movement of the piston and head may be adjusted by the nut 27. A shaft 30 is mounted in suitable bearings in the body 1, 75 as shown in Figure 2. The shaft 30 is provided with a ribbed head 31 which extends into the box-like chamber 16, and said shaft also carries a worm 31 which meshes with the gear teeth 28 on the nut 27. By rotating the shaft 30, the nut 27 may be conveniently adjusted. A spring 32 bears against the head 31 and locks it against rotation. The box-like chamber 16 is provided with a cover 33 which is secured in 80 position by a pin 34.

The governor is secured to the manifold of a motor and to the carburetor by bolts, not shown, which pass through the ears 35.

I have found that by removing the sleeve 6 and inserting in its place a sleeve with a greater or lesser contraction at the throat 7, I can satisfactorily govern motors of greater or lesser horse power with the same accuracy that would be attained by using governors which were either larger or smaller, to correspond with the horse power of the motors to which it is to be attached.

The operation of my governor is as follows: When the engine is running slowly the travel of the mixture from the carburetor through my governor to the engine will be comparatively slow and the impact of the mixture on the head 26 will not be sufficient to lift the head, and the parts to which it is secured, against the resistance of gravity and the spring 29. The weight of the head 26, and the parts to which it is secured, and the resistance of the spring 29, as adjusted by the nut 27, are such that when the flow of mix- 110

ture, and its velocity, is sufficiently increased by the increase in engine speed, the head will be lifted, carrying with it the piston 20 and the valve 22. The valve 22 as it is raised restricts the throat 3 and thereby causes the pressure above the valve to fall below the pressure within the body of the governor, the valve 22 being protected by the cup 10 from impact of the mixture against its base and thereby from exerting any lifting effect upon the piston or the parts to which it is attached. The pressure beyond the valve 22 is communicated through the passage 11 to the cylinder 8. As the valve 22 is raised this difference in pressure is rapidly increased and if the engine speed is maintained the difference in pressure will cause the piston 20 to rise and lift the valve 22 until the throat 3 is nearly closed, and further acceleration of the engine speed is prevented. When the valve 22 is in the closed position the clearance between the said valve and the throat 3 is such that a sufficient quantity of mixture may pass the valve to keep the engine running smoothly and prevent missing. By regulating the needle-valve 14 so as to partially close the passage 11 the lifting effect of the piston 20 may be accurately regulated. By regulating the resistance of the spring 19 through the nut 27 the engine speed at which the initial closing movement begins may also be accurately regulated, thereby enabling my governor to supply full charges of the mixture to the motor at all engine speeds which are substantially below the engine speed to which the governor has been adjusted.

The primary means which initiates the closing movement of the valve 22 is the head 26 and the secondary means, which is adapted to complete but would not initiate the closing of the movement of the valve 22, is the piston 20. My governor, as described, is so constructed that the parts move with the minimum of friction and it quickly and accurately responds to the varying conditions of the flow of mixture through it and can be easily and accurately adjusted while in position.

50. Claims:

1. A governor for internal combustion motors comprising in combination a passageway through which explosive mixture may pass to a motor, a discharge outlet of lesser diameter than said passageway a cylinder
55. mounted in said passageway around but not through which the explosive mixture may pass, a valve mounted in said cylinder and automatic means positioned upstream from said valve, for moving said valve toward said discharge outlet.

2. A governor for internal combustion motors comprising in combination a passageway through which explosive mixture may pass to a motor, a discharge outlet of lesser diameter than said passageway a cylinder mounted in said passageway around but not through which the explosive mixture may pass, a cylindrical valve mounted in said cylinder in operative relation to such discharge outlet and automatic means positioned upstream from said valve for moving said valve toward said discharge outlet.

3. A governor for internal combustion motors comprising in combination a passageway through which explosive mixture may pass to a motor, a discharge outlet of lesser diameter than said passageway, a cylinder mounted in said passageway around but not through which explosive mixture may pass, the interior diameter of such cylinder being substantially the same as the diameter of said outlet and the axes of such discharge outlet and cylinder being substantially coincident, a cylindrical valve mounted in said cylinder in operative relation to such discharge outlet and automatic means positioned upstream from said cylindrical valve for moving said valve toward said outlet.

4. A governor for internal combustion motors comprising in combination a shell having a passageway through which explosive mixture may pass to the motor, restricted at the discharge end thereof, a cylinder mounted in said passageway, a second cylinder of substantially the same diameter as said restricted throat located above said first mentioned cylinder and below said restricted throat, the axes of said cylinders and said throat being coincident, a passageway of relatively small diameter between said cylinders, a piston mounted in said first cylinder, a head mounted on the lower end of said piston in the path of the mixture as it passes through the governor and a cylindrical valve mounted within said second cylinder on the upper end of said piston.

June 8th, 1923.

RAYMOND HUFFORD.
